(57) **CLAIM**

The ornamental design for a soap dispenser, as shown and described.

DESCRIPTION

FIG. 1 is a front, left and top perspective view of a soap dispenser, showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, left and top perspective view of the soap dispenser in use state.

The broken lines shown in the drawings illustrate portions of the soap dispenser that form no part of the claimed design. Other broken lines illustrate environmental subject matter that form no part of the claimed design.

1 Claim, 9 Drawing Sheets
